(57) **CLAIM**

The ornamental design for a trim reveal extrusion, as shown and described.

DESCRIPTION

FIG. 1 is a perspective view of a trim reveal extrusion showing my new design; and,

FIG. 2 is a cross-sectional view thereof.

The trim reveal extrusion is shown with a symbolic break in its length. The appearance of any portion of the trim reveal extrusion between the lagged break lines form no part of the claimed design.

1 Claim, 1 Drawing Sheet

FIG. 1

FIG. 2
